TERENCE J. GOODWIN, OF SYRACUSE, NEW YORK.

PATTERN FOR DRAFTING SHIRT-SLEEVES.

SPECIFICATION forming part of Letters Patent No. 501,337, dated July 11, 1893.

Application filed February 13, 1893. Serial No. 462,101. (No model.)

To all whom it may concern:

Be it known that I, TERENCE J. GOODWIN, of Syracuse, in the county of Onondaga, in the State of New York, have invented new and useful Improvements in Shirt-Patterns, of which the following, taken in connection with the accompanying drawings, is a full, clear, and exact description.

My invention relates to improvements in patterns for drafting the sleeve pieces of shirts, and has for its object the production of a practical, simple, durable, and effective device consisting of adjustable plates or sections capable of ready adjustment for facilitating the drafting of a well fitting sleeve-piece for shirts; and to this end it consists in the detail construction and arrangement of parts, all as hereinafter more particularly described and pointed out in the claims.

In describing this invention, reference is had to the accompanying drawings, forming a part of this specification, in which like letters and figures indicate corresponding parts in all the views.

Figure 1 is a face view of my improved pattern having portions of its overlying parts broken away. Fig. 2 is a similar face view representing the pattern as somewhat expanded, and Figs. 3 and 4 are sectional views, taken respectively on lines —3—3—, Fig. 2, and —4—4— Fig. 1.

My present invention consists of a pattern, which is readily adjustable to any required size of sleeve-piece for enabling an operator to readily and correctly draft a sleeve-piece of the required size without the exercise of a high degree of skill. This pattern consists of the lengthwisely adjustable plate —A— for regulating the length of the central portion of the sleeve, a top plate composed of lengthwisely adjustable arms —B—B— extending laterally from one end of the plate —A— and having their upper edges curved downwardly from their inner ends for regulating the width of the upper or shoulder end of the sleeve-piece, a bottom plate consisting of lengthwisely adjustable arms —C—C— extending laterally from the opposite end of the plate —A— for regulating the lower or wrist end of the sleeve-piece, and the lengthwisely adjustable side plates —D—D— having their upper ends hinged to the outer ends

of the arms —B—B— and their opposite ends hinged to the corresponding ends of the arms —C—C— for regulating the length and inclination of the longitudinal sides of the sleeve-piece. The plate —A— consists of the sections —a—a'— having their inner or adjacent ends lapped one upon another and provided with lengthwise slots —a²—a³—. A 60 suitable lug —e— is secured to the lower or inner end of the section —a— and is formed with a shank —e'— registered with the slot —a³— in the section —a'— and with a shoulder —e²— resting upon the top face of said section —a'—. This lug serves to guide the sections —a—a'— in their lengthwise movement, and this guiding action is facilitated by the shank —f— of a clamp —F—, which may be of any desirable construction for 70 clamping said sections —a—a'— in their adjusted position and guiding said sections in their adjustable movement. As best seen at Fig. 3 the shank —f— of the clamp —F— is passed through an opening —a⁴— in the 75 upper or inner end of the section —a'—, is registered with the slot —a²— in the section —a—, and is provided at one end with a shoulder —f'— bearing against the under face of the section —a—. A nut —f²— is 80 movable on the opposite end of the shank —f—, and bears against the upper face of the section —a'—. The section —a— of the plate —A— is provided with a scale —1— along which is movable the upper edge —a⁵— of the 85 section —a'—. This scale —1— is formed with graduations —20—, —21—, —22—, &c., to —27— extending from the central portion of the section —a— toward its lower end, and serves to regulate the length of the central 90 portion of the sleeve-piece. It will thus be readily apparent that the plate —A— is quickly adjustable lengthwisely until the desired graduation is exposed in front of the edge —a⁵— of the section —a'—, and that its 95 sections —a—a'— are then held positively and effectively in their adjusted position by the clamp —F—.

The arms —B—B— for regulating the upper or shoulder end of the sleeve-piece each 100 consist of sections —b—b'—, the sections —b—b— being fixedly secured to one end of the plate —A— in any desired manner as by rivets —b²— and the sections —b'—b'— be-

ing movable lengthwise upon the sections $b-b$. The upper edges b^3-b^3 of the sections $b-b'$ of each arm B are curved downwardly from their inner ends, and 5 said sections are formed with lengthwise slots b^4 , which are preferably concentric with the edges b^3 . The outer end of each section b is provided with a lug e , which is registered with the slot b^4 in the corresponding section b' , and is of the same construction as the lug e previously described. The inner end of each section b' is provided with a clamp F similar to the clamp F previously described, and this 15 latter clamp F is movable lengthwise in the slot b^4 in the corresponding section b , and serves to firmly secure together the sections of the arms B provided therewith when said sections are adjusted to the 20 desired position. Each of the sections b is provided with a scale 2 along which is movable the inner edge b^5 of the corresponding section b' , and this scale is provided with graduations $31\frac{1}{2}$, 33 , 25 $34\frac{1}{2}$, 36 , $37\frac{1}{2}$ to 51 extending along the slot b^4 in said section b from its inner end outwardly.

The arms $C-C$ for regulating the lower or wrist end of the shoulder piece are each 30 composed of sections $c-c'$, the sections $c-c$ being fixedly secured to the opposite or lower end of the plate A by rivets or other securing means c^2 , and the sections $c-c'$ being movable lengthwise upon 35 the sections c . The lower edges c^3-c^3 of the sections $c-c'$ of each arm C are preferably curved downwardly from their inner ends, and said sections are provided with lengthwise slots c^4 extending in a 40 plane perpendicular to that of the plate A . The outer end of each of the sections c is provided with a lug e , which is similar to the lug e previously described, is movable in the slot c^4 in the overlapping section c' , and serves to guide said overlapping section in its movement upon said section c . A suitable clamp F similar to the clamp F previously described, is supported in the inner end of each of the sections 45 c' and the shank f of said clamp is movable in the slot c^4 in the corresponding section c , and serves to hold the overlapping section c' in its adjusted position. Each of the sections c is provided with a 50 scale 3 along which is movable the inner edge c^5 of the corresponding section c' , and this scale is provided with graduations 32 , 36 , 40 , to 52 extending along the slot c^4 in said section c from 55 its inner edge outwardly.

The plates $D-D$ for regulating the length and inclination of the sides of the sleeve-piece are each of similar construction, and are composed of sections $d-d'$, the 60 section d being hinged by a pivotal pin d^2 to the outer end of the section b' of the corresponding arm B , and the sec-

tion d' being hinged by a pivotal pin d^3 to the outer end of the section c' of the corresponding arm C . The adjacent or inner ends of the sections $d-d'$ are formed with lengthwise slots d^4 , and movable in said slots are two lugs $e-e$, which are of similar construction to the lug e previously described, and are secured 75 respectively to the lower end of the section d and to the upper end of the section d' . The outer edges of the upper ends of the sections $d-d$ of said plates $D-D$ are concavely curved, and the outer edge of the lower ends of the sections $d-d'$ are convexly curved for giving the edges of the corresponding portions of the sleeve-piece the proper curve when drafted by marking around the outer edge of my improved pattern. 85

It will be readily understood by one skilled in the art that, as the plate A is adjusted lengthwise in conformity with the desired length of the sleeve-piece, the side plates $D-D$ are also adjusted lengthwise, and 90 that their sections $d-d'$ swing upon their pivotal pins d^2-d^3 for permitting the lengthwise adjustment of the plate A , and that these sections also swing on their pivotal pins for facilitating the adjustment 95 of the arms $B-B$, $C-C$.

In order that my invention may be readily understood I have shown the same at Fig. 2 as adjusted for the sleeve-piece of a sleeve twenty-three inches long designed for a shirt 100 having a breast measurement of thirty-six inches; it being understood that the breast measurement of the shirt governs the width of the upper portion of the sleeve. Consequently the division 23 is exposed directly in front of the edge a^5 , and the division 36 of the scales 2 and 3 are exposed at the inner sides of the edges b^5-c^5 of the sections $b-c'$ of the arms $B-C$ at the opposite ends of the plate A . My pattern may be similarly 110 adjusted to any other measurement of sleeve, and, after the pattern is adjusted, the sleeve-piece may be readily drafted by placing the pattern upon the fabric and marking around the outer edge of said pattern. It is apparent that one of the arms B , the corresponding arm C , and the interposed side plate D may be dispensed with, and that a sleeve-piece can then be readily drafted by 115 folding the fabric and placing the folded edge directly beneath the longitudinal center line of the lengthwise plate A , and by then marking around the edges of the remaining plate D and the arms $B-C$. It is also evident that, if desired, the central plate A may be dispensed with, and the outer 120 ends of two of the corresponding sections of the side plates $D-D$, as the sections $d-d$, may then be rigidly secured to their supporting arms as $B-B$, and the outer ends of the remaining corresponding sections of the side plates $D-D$, as the sections $d-d'$ being pivotally secured to their 125

supporting arms as —C—C— will permit of the lengthwise expansion of my improved pattern. This is, however, no material modification of my present invention.

5 The operation of my invention will be readily perceived from the foregoing description and upon reference to the drawings, and it will be particularly understood that the same is simple, practicable, durable, and effective.

10 Having thus fully described my invention, what I claim as new, and desire to secure by Letters Patent, is—

1. The herein described pattern for the sleeve-piece of a shirt, the same comprising a 15 lengthwisely adjustable plate —A— having a substantially straight longitudinal edge, a lengthwisely adjustable arm —B— extending laterally from one end of the plate —A— and having its upper edge curved downwardly

20 from its inner end, said arm —B— consisting of lapping sections, one of which is fixedly secured to the plate —A— a lengthwisely adjustable arm —C— extending laterally from the opposite end of the plate —A— and consisting of lapping sections, one of which is fixedly secured to the plate —A—, and a lengthwisely adjustable plate —D— having one extremity hinged to the outer end of the arm —B— and the other extremity hinged to 25 the corresponding end of the arm —C—, substantially as and for the purpose set forth.

2. The herein described pattern for the sleeve-piece of a shirt, the same comprising a lengthwisely adjustable plate —A— com-

35 posed of a section —a— provided with a scale —1— and a section —a'— movable rectilinearly along said scale —1— a lengthwisely adjustable arm —B— extending laterally from one end of the plate —A— and having its upper edge curved downwardly from its inner end, said arm —B— being composed of a section —b— fixedly secured to one end of the plate —A— and provided with a scale —2— and a section —b'— movable lengthwisely of

40 the scale —2—, a lengthwisely adjustable arm —C— extending laterally from the opposite end of the plate —A—, said arm —C— being composed of a section —c— fixedly secured to the opposite end of the plate —A— and

45 provided with a scale —3— and a section —c'— movable lengthwise of the scale —2—, and a lengthwisely adjustable plate —D— having one extremity hinged to the outer end of one of the sections of the arm —B— and

50 having its other extremity hinged to the corresponding end of one of the sections of the arm —C—, substantially as and for the purpose set forth.

3. The herein described pattern for the 55 sleeve-piece of a shirt, the same comprising a lengthwisely adjustable plate —A— for regulating the length of the central portion of the sleeve-piece, an upper plate composed of lengthwisely adjustable arms —B—B— fixedly secured to the upper end of the plate —A— and having their upper edges curved downwardly from their inner ends, a length-

wisely adjustable plate composed of arms —C—C— fixedly secured to the lower end of the plate —A— and formed of less length than the arms —B—B—, and lengthwisely adjustable downwardly inclining side plates —D—D— having their upper extremities hinged to the outer ends of the arms —B—B— and their opposite extremities hinged to the outer ends of the arms —C—C—, substantially as and for the purpose set forth.

4. The herein described pattern for the sleeve-piece of a shirt, the same comprising a lengthwisely adjustable plate —A— for regulating the length of the central portion of the sleeve-piece, an upper plate composed of lengthwisely adjustable arms —B—B— fixedly secured to the upper end of the plate —A— and having their upper edges curved downwardly from their inner ends, a lengthwisely adjustable plate composed of arms —C—C— fixedly secured to the lower end of the plate —A— and formed of less length than the arms —B—B— and having their lower edges curved downwardly from their inner ends, and lengthwisely adjustable downwardly inclining side plates —D—D— having their upper extremities hinged to the outer ends of the arms —B—B— and their opposite extremities hinged to the outer ends of the arms —C—C— and having the upper portions of their outer edges concavely curved and the lower portions of said outer edges convexly curved, substantially as and for the purpose described.

5. The herein described pattern for the sleeve-piece of a shirt, the same comprising a lengthwisely adjustable plate —A— for regulating the length of the central portion of the sleeve-piece, said plate —A— being composed of a section —a— provided with a scale —1— and a section —a'— movable lengthwise of said scale, an upper plate composed of lengthwisely adjustable arms —B—B— fixedly secured to the upper end of the plate —A— and having their upper edges curved downwardly from their inner ends, said arms —B—B— being composed of sections —b—b— fixedly secured to the plate —A— and provided with scales —2—2— and sections —b'—b'— movable lengthwise of the scales —2—2—, a lengthwisely adjustable plate composed of arms —C—C— fixedly secured to the lower end of the plate —A— and formed of less length than the arms —B—B— and having their lower edges curved downwardly from their inner ends, said arms —C—C— being composed of sections —c—c— fixedly secured to the plate —A— and provided with scales —3—3— and sections —c'—c'— movable lengthwise of the scales —3—3—, and lengthwisely adjustable downwardly inclining side plates —D—D— having their upper extremities hinged to the outer ends of the sections —b—b— of the arms —B—B— and their opposite extremities hinged to the outer ends of the sections —c'—c'— of the arms —C—C—

55 and having the upper portions of their outer

edges concavely curved and the lower portions of said outer edges convexly curved, substantially as and for the purpose specified.

6. The herein described pattern for the sleeve-piece of a shirt, the same comprising lengthwisely adjustable arms —B—B— having their adjacent ends relatively fixed and having curved upper edges, lengthwisely adjustable arms —C—C— of less length than the former arms —B—B—, having their adjacent ends relatively fixed and lengthwisely adjustable side plates —D—D— consisting oflapping sections movable upon each other in rectilinear planes parallel with the planes of extension of said side plates —D—D— and

having corresponding ends secured to the outer ends of the arms —B—B— and having their opposite ends secured to the outer ends of the arms —C—C—, substantially as described.

In testimony whereof I have hereunto signed my name, in the presence of two attesting witnesses, at Syracuse, in the county of Onondaga, in the State of New York, this 27th day of January, 1893.

TERENCE J. GOODWIN.
